UNITED STATES PATENT OFFICE.

GILES F. FILLEY, OF ST. LOUIS, MISSOURI.

DOOR FOR STOVE-OVENS.

SPECIFICATION forming part of Letters Patent No. 246,606, dated September 6, 1881.

Application filed January 24, 1881. (No model.)

To all whom it may concern:

Be it known that I, GILES F. FILLEY, of St. Louis, Missouri, have made a new and useful Improvement in Doors for Cooking Stoves and Ranges, of which the following is a full, clear, and exact description, reference being had to the annexed drawings, making part of this specification, in which—

Figure 1 is a side elevation of a cooking stove or range oven door having the improvement, and Fig. 2 a vertical transverse section thereof.

The same letters denote the same parts.

I have heretofore made an improvement in cooking stoves and ranges the aim and effect of which is to cause the outer air to pass directly into and to circulate through the oven wherein the articles are being cooked, and thence out therefrom.

The present invention is mainly an improved means for admitting the outer air directly into and discharging it from the oven; and it consists in providing the door or doors of a stove or range oven with a register of such size and so arranged that the outer air can pass through the lower openings of the register into the lower part of the oven and be discharged through the upper openings of the register from the upper part of the oven.

The invention is carried out by inserting in the oven door or doors a register which nearly or quite fills the main portion of the door, as in the drawings, wherein—

A represents a door of a cooking stove or range oven, and which, saving as modified by the present improvement, may be of the usual construction.

B represents the register in question, extending, as seen, throughout the main portion *a* of the door. The register is preferably made to open more in its upper half than in its lower half. This may be effected by making the register-openings *b b* of uniform size, but more in number in the upper portion of the register, as shown in Fig. 1.

In operation the air enters the oven through the lower openings and leaves the oven through

the upper openings of the register, as indicated by the arrows.

The register can be opened more or less widely, according to the amount of air it is desired to have pass through the oven.

Fine gauze or finely-perforated metal C may be used in connection with the register, both to subdivide the heat and air currents and as a guard. The gauze may be fixed in position opposite the register-openings by any suitable means.

In Fig. 2, F represents the oven-top, E the side plate of the stove or range, and G the oven-bottom.

In place of a rotating register, C, such as shown, a slide-register may be used.

If desired, a small register, D, may be inserted in the part *a'* of the door.

I am aware that an oven-door has had a small register inserted in the center of the door. Such register, however, did not extend throughout, or even nearly throughout, the main portion of the door, and it could not be used to promote an air-circulation in the manner contemplated by the present improvement.

I claim—

1. A cooking stove or range oven door or doors having a register arranged and extended throughout the main portion of the door, as and for the purpose set forth.

2. A cooking stove or range oven door or doors having the register B and gauze C, said register being arranged and extended as and for the purpose set forth.

3. The combination of the door A and register B, said register having a larger opening in its upper than in its lower half, substantially as described.

4. A cooking stove or range oven door or doors having a register, B, arranged and extended as described, and the register D, in combination.

GILES F. FILLEY.
